UNITED STATES PATENT OFFICE

OWEN H. SPENCER, OF INDIANAPOLIS, INDIANA

ENGINE-COOLING MEANS

Application filed March 9, 1929. Serial No. 345,810.

This invention relates to cooling means for engines, and particularly to the internal combustion type, and one feature of the invention is the provision of a fan structure adapted to direct a blast of air against the exterior of an engine for cooling the same.

A further feature of the invention is the provision of means for collecting a portion of the blast of air for cooling the interior 10 of the engine.

A further feature of the invention is the provision of means for conducting the collected air blast to certain parts of the engine.

15 A further feature of the invention is the provision of means for causing the air to enter the collecting chamber.

Other objects and advantages will be hereinafter more fully set forth and pointed out 20 in the accompanying specification.

In the accompanying drawings which are made a part of this application,

Figure 1 is an end elevation of an engine with the fan mechanism thereon.

25 Figure 2 is a top plan view of an engine with parts broken away and in section.

Figure 3 is a detail sectional view of the air collecting mechanism, as seen on line 3-3, Fig. 1.

30 Referring to the drawings in which similar reference numerals designate corresponding parts throughout the several views, 1 indicates the cylinders of an engine, preferably of the internal combustion type and 2 indicates a fan structure adapted to direct a blast of air against the exterior surfaces of the engine for cooling the same.

As certain portions of the cylinders of an engine of this type are heated to a greater 40 degree than other parts, means is provided for collecting portions of the air blast as it is directed toward the parts of the engine and conveying it to the superheated parts, comprising a duct 3, which extends from a 45 point adjacent the path of the fan blades to the several cylinders 1, said duct being substantially at right angles to the fan structure and connected at intervals throughout its length with air chambers 4 around the cylinders 1. The mouth 5 of the duct 3 is open,

so that a portion of the blast of air created by the fan structure will enter therein and be carried to the various chambers 4, and to induce the blast of air to enter the mouth 5, bars 6 are disposed across the open end of the mouth 5, preferably at an angle to a line intersecting the axis of the fan structure and the duct. By arranging the bars 6 in this manner, the current of air, as it is forced past the open end of the duct 3, will be somewhat interrupted and caused to enter the mouth 5 with sufficient force and volume to be directed thru the duct 3 and chambers 4.

As the chambers 4 surround the cylinders at the point thereon receiving a greater 55 amount of heat than the remainder of the cylinders, the extra supply of cooling medium will maintain the cylinders at these points at substantially the same temperature as the remainder of the cylinders, with no extra 60 cost or greater or separate blast of air.

While the description and drawings illustrate in a general way certain instrumentalities which may be employed in carrying the invention into effect, it is evident that many modifications may be made in the various details, without departing from the scope of the appended claims, it being understood that the invention is not restricted to the 70 particular examples herein described.

I claim as my invention:

1. In a cooling means for an engine, the combination with the cylinders of an engine, of a fan for directing a blast of air from the front to the rear end of said engine, and 85 means extending from the front to the rear cylinders and substantially at right angles to said fan for gathering and conveying a portion of the blast of air to specified parts of the cylinders.

2. In a cooling means for an engine, the combination with the cylinders of an engine, having air chambers therein, of a fan forwardly of said engine for directing a blast of air against said cylinders, and means substantially at right angles to said fan for gathering a portion of the air blast and conveying the same to said chambers.

3. In a cooling means for an engine, the combination with the cylinders of an engine 100

having air chambers therein, and means for directing a blast of air against said cylinders, of a duct substantially at right angles to said fan having a flared open end adapted to gather a portion of said air blast and convey

5 the same to said chambers.

4. In a cooling means for an engine, the combination with the cylinders of an engine having air receiving chambers formed there-around, and means for directing a blast of air
10 against said cylinders, of a duct adapted to convey air to said chambers, and means ex-
tending across the open end of said duct against which a portion of the air blast is
15 directed for gathering and causing a portion of said blast of air to enter said duct.

In testimony whereof, I have hereunto set
my hand on this the 5th day of March, 1929,
A. D.

OWEN H. SPENCER.
